US0D1046562S

(12) **United States Design Patent** (10) **Patent No.:** **US D1,046,562 S**
(45) **Date of Patent:** **** Oct. 15, 2024**

(54) **HOLDER**

(71) Applicants: **Stavros Korovilas**, Skokie, IL (US); **Sarah C. Severson**, Schaumburg, IL (US); **James David Shaw**, Chicago, IL (US); **Corey Alan Davis**, Chicago, IL (US)

(72) Inventors: **Stavros Korovilas**, Skokie, IL (US); **Sarah C. Severson**, Schaumburg, IL (US); **James David Shaw**, Chicago, IL (US); **Corey Alan Davis**, Chicago, IL (US)

(73) Assignee: **BEVZI, LLC**, Skokie, IL (US)

(**) Term: **15 Years**

(21) Appl. No.: **29/847,289**

(22) Filed: **Jul. 22, 2022**

(51) LOC (14) Cl. **07-09**

(52) U.S. Cl.

USPC **D7/619.1**; D7/624.1

(57) **CLAIM**

The ornamental design for a holder as shown and described.

DESCRIPTION

FIG. 1 is a perspective view of a holder, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the figures illustrate portions of the holder that form no part of the claimed design.

1 Claim, 2 Drawing Sheets
